[57] CLAIM

The ornamental design for a shoe sole, as shown.

DESCRIPTION

FIG. 1 is a left side elevational view thereof;
FIG. 2 is a front elevational view thereof;
FIG. 3 is a right side elevational view thereof;
FIG. 4 is a rear elevational view thereof;
FIG. 5 is a top plan view thereof;
FIG. 6 is a bottom plan view thereof;
FIG. 7 is a cross-sectional view taken along line 8—8 in FIG. 2; and,
FIG. 8 is a perspective view end view of the shoe sole.
The article of the present design is a shoe sole which is attached to the upper part of a shoe. The design is symmetrical in respect of the corresponding opposite shoe sole.
